ANTISEPTIC DETERGENT COMPOSITIONS

ARTIFICIAL DETERGENT COMPOSITIONS
Steven J. Fitch, Creve Coeur, and Riyad R. Irani, Olivette,
Mo., assignors to Monsanto Company, a corporation of
Delaware
No Drawing. Filed Dec. 23, 1963, Ser. No. 332,882
7 Claims. (Cl. 252—106)

This invention relates to new and novel detergent compositions and more particularly to detergent compositions containing a bacteriostatic agent. 10

Detergents of themselves are not effective in preventing or arresting the growth or action of micro-organisms such as the Staphylococci, i.e., *Staphylococcus aureus*, either by inhibiting their activity or by destroying them. 15 Thus, when such action is desired bacteriostatic agents must be incorporated into the detergent composition to fulfill this function. However, none of the known bacteriostatic agents which are effective in the presence of detergent compositions aid in the cleansing action and, in fact, some are deleterious to such action. As can be appreciated, therefore, a bacteriostatic agent which also exhibits surface active properties and thereby aids the detergent in the cleansing action would represent an advancement in this art. 20

It is, therefore, an object of this invention to provide improved antiseptic detergent compositions.

It is a further object of this invention to provide detergent compositions having incorporated therein a bacteriostatic agent which exhibits surface active properties.

Other objects will become apparent from a reading of the following detailed description and the claims appended hereto.

It has been found that dialkyl esters of long-chain alkyl phosphonates having the formula

wherein R_1 is a member selected from the group consisting of alkyl, hydroxy-alkyl and halo-alkyl containing from about 8 to 18 carbon atoms and preferably from 10 to 14 carbon atoms and R_2 and R_3 are lower alkyl groups (1 to 5 carbons) and preferably containing from 1 to 2 carbon atoms, unexpectedly exhibit bacteriostatic properties as well as surface active properties as will be more fully discussed hereinafter.

Compounds of the present invention which are suitable for use according to the teachings contained herein incide:

- (1) dimethyl octylphosphonate
  - (2) dibutyl dodecylphosphonate
  - (3) dipropyl decylphosphonate
  - (4) diethyl dodecylphosphonate
  - (5) dimethyl octadecylphosphonate
  - (6) diethyl hexadecylphosphonate
  - (7) dipropyl tetradecylphosphonate
  - (8) dibutyl tetradecylphosphonate
  - (9) dimethyl decylphosphonate
  - (10) diethyl decylphosphonate
  - (11) diethyl 1-hydroxydodecylphosphonate
  - (12) diethyl 1-hydroxydecylphosphonate
  - (13) dimethyl 1-chlorododecylphosphonate
  - (14) diethyl 3-bromodecylphosphonate

The dialkyl esters of long-chain alkyl phosphonates of the present invention can be prepared by many various methods which include reacting a long-chain n-alkyl halide (chloride or bromide) with a tri-lower alkyl phosphite under conditions of elevated temperatures, i.e. about

2

The following examples are presented to illustrate the invention, with parts by weight being used in the examples unless otherwise indicated.

Example 1

Into a reaction vessel are charged about 260 parts of trimethyl phosphite and about 442 parts of dodecylbromide. The reaction mixture is heated to about 150° C. for about 24 hours and the resulting products distilled in vacuo to yield about 186 parts of dimethyl dodecylphosphonate (B.P. 137° C./2 mm.).

Example 2

20 In the same manner as indicated in Example 1, about 249 parts of trimethylphosphite and about 500 parts of tetradeethyl bromide were reacted to yield about 356 parts of dimethyl tetradeethyl phosphonate (B.P. 155° C./.3 mm.).

Example 3

In the same manner as indicated in Example 1, about 348 parts of triethylphosphite and about 442.4 parts of dodecyl bromide were reacted to yield diethyl dodecyl phosphonate (B.P. 159° C./1.1 mm.).

The term "detergent" includes soap, i.e., an alkali metal or amine salt of a fatty acid and/or fatty acid mixtures, and synthetic detergents, particularly of the anionic, non-ionic and amphoteric classes, including mixtures of these. The term "antiseptic detergent composition" refers to those detergent compositions which are satisfactory detergents and which are effective against *Staphylococcus*.

The dialkyl esters of long-chain alkyl phosphonates of the present invention have been found to not only exhibit surface-tension-reducing properties in aqueous systems but also to exhibit effective bacteriostatic properties in such systems in the presence of detergent compositions. In addition, these bacteriostatic agents neither impart an unpleasant odor nor discolor the finished detergent composition. Furthermore, the new antiseptic detergent compositions are not irritating to the skin. It is, of course, a distinct advantage of the bacteriostatic agents of the present invention that they additionally aid the detergent composition in its cleansing action by exhibiting surface active properties in aqueous systems.

The amounts of the dialkyl esters of long-chain alkyl phosphonates which are suitable for use in detergent compositions can vary depending upon the end use application of the detergent composition, such as soap bars, hair shampoo and the like and, in general, any amount which is antiseptically effective, i.e., effective against *Staphylococcus*, can be used with amounts below about 50% by weight of the detergent being usually acceptable and amounts from about .05% to 10% being preferred. Under some circumstances, some bacteriostatic activity can be found as low as .001% by weight of the detergent.

The invention is not to be limited to any particular method of preparing the detergent composition containing the bacteriostatic agent. The bacteriostatic agent can be mechanically mixed in, crutched in the detergent in the form of a slurry, or dissolved in a solution of the detergent. In addition, the bacteriostatic agent can be admixed with the detergent in any of the forms in which the detergent is manufactured in, as well as being added simultaneously or separately to an aqueous solution. In any event, the bacteriostatic agent is intended to be used

with the detergent at the time of application as a cleansing agent.

The resulting antiseptic detergent composition, that is, the detergent and the bacteriostatic agent, of the present invention is generally effective when used in aqueous systems in conventional amounts such as is normally used with detergent compositions and which is generally about .2% concentration or below.

In order to illustrate the surface active properties of the bacteriostatic agent of the instant invention, the following table presents the surface tensions in dynes per centimeter of solutions at the indicated concentrations of agents and distilled water at 25° C. as determined by the Du Nuoy principle using the Fisher tensiomat. The surface tension of water is about 72.8 dynes/cm. at this temperature. A reduction of the surface tension of water to about 30 dynes in 0.1% solution is considered excellent and if this reduction is maintained practically unchanged to a dilution as low as .001%, the material is considered an extremely active surface-tension-reducing agent.

TABLE 1

Compound	Surface Tension in dynes/cm. at 25° C.				
	1.0%	.1%	.01%	.001%	.0001%
(1) Dimethyl dodecyl phosphonate	26.0	26.6	27.3	26.9	45.5
(2) Dimethyl tetradecyl phosphonate	25.3	25.3	25.4	28.0	40.6
(3) Diethyl dodecyl phosphonate	27.7	27.8	27.8	28.7	

As previously mentioned, the bacteriostatic agents of the present invention are effective in controlling bacterial growth in the presence of detergents such as an Ivory brand neutral high grade toilet soap which is a mixture of alkali metal salts of fatty acids analyzing about 46 weight percent oleic and linoleic acid, about 14 weight percent stearic acid, about 30 weight percent palmitic acid and about 10 weight percent of lower fatty acids (myristic, lauric, etc.), and when incorporated in such a soap in a weight ratio of one part to 50 parts soap are effective in low concentrations (less than about 100 p.p.m.) against an inoculum of a standard culture of *Micrococcus pyogenes* var. *aureus* (*Staphylococcus aureus*) of standard resistance in a Sabourard's dextrose agar medium. Diethyl dodecyl phosphonate appears to exhibit the greatest effectiveness, i.e., effective at concentrations as low as about 1 to 20 p.p.m., and is therefore preferred.

Comparable effectiveness can also be obtained when using other soaps such as Lux brand solid neutral white toilet soap (a mixture of alkali metal salts of fatty acids whose fatty acid content analyzes about 45% oleic and linoleic, about 30% palmitic acid, about 10% stearic acid and about 15% lower fatty acids) as well as anionic, nonionic and amphoteric synthetic detergents. Anionic surface active compounds can be broadly described as compounds which contain hydrophilic and lyophilic groups in their molecular structure and which ionize in an aqueous medium to give anions containing the lyophilic group. These compounds are usually the alkali metal salts of organic sulfonates or sulfates, particularly the sodium salts, such as alkyl aryl sulfonates (e.g. sodium dodecyl benzene sulfonate), sulfate of straight chain primary alcohols (e.g., sodium lauryl sulfate) and the like. Nonionic surface active compounds can be broadly described as compounds which do not ionize but acquire hydrophilic characteristics from an oxygenated side chain, usually polyoxyethylene, while the lyophilic part of the molecule may come from fatty acids, phenols, alcohols, amides or amines. For example purposes only, the polyethylene oxide condensates of alkyl phenols (e.g., condensation product formed from 1 mole nonyl phenol and

10 moles ethylene oxide), the condensation products of aliphatic alcohols and ethylene oxide (e.g., condensation product formed from 1 mole tridecanol and 12 moles ethylene oxide) are suitable nonionic surface active compounds in practicing the invention. Amphoteric surface active compounds can be broadly described as compounds which have both anionic and cationic groups in the same molecule. Examples of such compounds include sodium N-methyl taurate and sodium N-coco beta amino propionate.

While a detergent composition of the present invention need contain only a detergent and the diethyl esters of long-chain phosphonates, it will be appreciated that the incorporation in the mixture of additional ingredients commonly used with cleansing agents, such as perfume, builders (e.g. sodium tripolyphosphate), anti-redeposition agents (e.g., carboxymethylcellulose), brightening agents (e.g., fluorescent dyes) and the like, is contemplated as being within the invention.

A further understanding of the detergent compositions described herein and processes for preparing the compositions will be obtained from the following specific examples which are intended to illustrate this invention, but not to limit the scope thereof, parts and percentages being by weight unless otherwise indicated.

Example 4

A detergent composition is formulated as follows:

Additive:	Parts
Soap comprised of sodium salts of fatty acids derived from coconut oil (primarily lauric acid) (15 to 20%); sodium salts of fatty acids derived from tallow (approximately 40% stearic acid, 30% oleic acid, and 30% palmitic) (80 to 85%)	98
Diethyl dodecyl phosphonate	2

The above composition is prepared by melting the soap in a suitable vessel at about 60 to 70° C. and adding the phosphonate to the soap with agitation. The admixture is then poured into a suitable mold and allowed to solidify by cooling to room temperature (about 25° C.).

Example 5

A liquid detergent emulsion composition is formulated as follows:

Additive:	Parts
Water	46.1
Sodium carboxymethylcellulose (95% by weight)	.5
Fluorescent dye	.025
Disodium acid pyrophosphate	5.0
Nonionic organic active (nonyl phenol-ethylene oxide condensate)	10.0
Maleic anhydride-ethylene copolymer	1.0
Tetrapotassium pyrophosphate	20.0
Potassium hydroxide (45% by weight)	6.7
Sodium silicate (Na ₂ O:SiO ₂ of 1:2) (44.0% by weight)	10.0
Diethyl dodecyl phosphonate	1.0

The above composition is prepared by heating the water to about 60° C. and thereafter adding the above additives to the water in a mixer in their above listed order, each additive being added and mixed under high shear agitation over a period of about 1 to about 7 minutes while ensuring that the temperature of the mix does not exceed about 80° C.

Example 6

An antiseptic shampoo composition is formulated as follows:

Additive:	Parts
Triethanol lauryl sulfate	60
Methyl cellulose	2

5

	Parts
Propylene glycol	4
Potassium stearate	6
Water	130
Diethyldodecyl phosphonate	2

The above composition is prepared by melting the potassium stearate at about 60 to 70° C. and adding thereto the triethanol lauryl sulfate, methyl cellulose, propylene glycol and diethyl dodecyl phosphonate until the mixture is well mixed and blended and thereafter adding the water in such a manner as to prevent aeration.

What is claimed is:

1. An antiseptic detergent composition consisting essentially of a detergent selected from the class consisting of soap and organic synthetic detergents selected from the class consisting of non-soap anionic, nonionic and amphoteric surfactants and, as a bacteriostatic agent, in at least an antiseptically effective amount, a dialkyl ester of a long chain alkyl phosphonate having the following formula 15 20

wherein R_1 is a member selected from the group consisting of alkyl and halo-alkyl containing from about 8 to 18 carbon atoms and R_2 and R_3 are lower alkyl groups containing from 1 to 5 carbon atoms.

2. The antiseptic detergent composition of claim 1,

6

wherein R_1 contains from 10 to 14 carbon atoms and R_2 and R_3 contain from 1 to 2 carbon atoms.

3. The antiseptic detergent composition of claim 2, wherein said dialkyl ester of a long chain phosphonate is present in amounts below about 50% by weight of said composition.

4. The antiseptic detergent composition of claim 3, wherein said detergent is soap.

5. The antiseptic detergent composition of claim 3, wherein said detergent is a synthetic detergent selected from the class consisting of non-soap anionic, nonionic and amphoteric surfactants.

6. The antiseptic detergent composition of claim 2, wherein said dialkyl ester of a long chain alkyl phosphonate is diethyl dodecyl phosphonate.

7. The antiseptic detergent composition of claim 6, wherein said diethyl dodecyl phosphonate is present in amounts from about 0.05% to 10% by weight of said detergent composition.
